CLOTHES WASHING MACHINE

Hermann Hill, Rochester, N. Y., assignor to Easy
Washing Machine Corporation, Syracuse,
N. Y., a corporation of Delaware

Application September 8, 1933, Serial No. 688,635

3 Claims. (Cl. 259—101)

This invention relates to certain new and useful improvements in machines for washing clothes and more particularly to a novel dolly or agitator therefor.

5 An object of my invention is to provide a dolly of simple construction adapted to secure an effective washing action on the clothes.

A further object of my invention is to provide 10 a dolly for a washing machine which is adapted to circulate and agitate the contents of the vat, and at the same time effect a substantial vacuum cup action on the clothes.

More specifically, my invention contemplates 15 the provision of an oscillatable dolly for a washing machine having cup-shaped blades which are adapted when the dolly is oscillated to exert a substantial vacuum cup action on the clothes entirely beneath the surface of the cleansing fluid.

Other objects and advantages relating to the 20 structure and form and relation of the parts thereof will more fully appear from the following description, taken in connection with the accompanying drawings, in which:

Figure 1 is a view of my novel dolly in cross section mounted in a washing vat.

25 Figure 2 is a perspective view of the dolly showing the cup formation.

Figure 3 is a sectional plan view taken on the line 3—3, Figure 1.

Figure 4 is a perspective view of an alternate 30 form of my novel dolly.

Figure 5 is a cross sectional plan view of the dolly shown in Figure 4.

My novel agitator comprises a central post or 35 body portion 11 which is mounted in a vat 12 substantially centrally thereof. The bottom of the vat is provided with an opening for the reception of one end of an upstanding sleeve 13 secured to the bottom of the vat 12 in any suitable watertight manner. The sleeve 13 is provided with a portion 14 of reduced internal diameter constituting 40 an upper bearing for an oscillatory dolly shaft 16 which extends upwardly from a point without the vat to a point above the bearing 16.

45 Any usual and well known means may be provided for oscillating the dolly shaft 16 through a desirable arc, for instance 200 degrees, more or less, and I have here shown a dolly oscillating mechanism generally indicated by the numeral 2 50 which is mounted below the vat 12 and partially enclosed by a depending apron 18. A gear 19, mounted on the dolly shaft 16, is oscillated by segmental gear or rack 21 which is reciprocated from any suitable source of power.

55 The dolly shaft 16 projects above the bearing

14 and is formed at its upper end with lengthwise splines or grooves 22 for inner engagement with corresponding splines or grooves on a bearing member 23 permanently secured within the upper closed end 24 of the central body portion 11. The dolly is further supported at its lower end by a bearing member 26 fixed to the internal periphery of the central body portion 11 which is shouldered at 27 for reception of the bearing. The bearing member fits snugly on the sleeve 13 and rotates 10 with respect thereto. In this manner, a driving connection and support for the dolly is provided by the upper splined bearing member 23 and the dolly is guided by the upper and lower guide bearings 14 and 16 respectively. 15

Extending outwardly from the lower part of the central body portion in a position to contact with the clothes to be washed at substantially the bottom of the vat are a plurality, preferably a pair, of agitating blades 29. These blades preferably as shown in Figure 1 extend substantially 20 radially outwardly from the post or body portion 11 and are disposed substantially diametrically opposite each other and extend vertically about one-half the length of the post 11 which projects above the normal level of washing fluid in the tub. The blades merge smoothly into the central body portion and each of the blades is rounded on one side to form a substantially hemi-spherical surface as at 31 while the other side is hollowed out as at 32 to a substantial depth to provide a cup-shaped formation which, when the dolly is oscillated, will exert a substantial vacuum cup action on the clothes. 25

In Figures 4 and 5, I have shown an alternate 30 form of my novel dolly in which the cup-shaped blades are elongated in a direction parallel to the long axis of the central stem whereby when the agitator is oscillated in the washing vat, substantially the entire contents of the vat from the bottom thereof to the surface of the cleansing fluid is subjected to an effective vacuum cup action. 35

In operation, when the dolly is rotated in one direction, for example, a counter-clockwise direction, as shown in Figure 1, because of the vacuum cup action, the clothes adjacent the bottom of the vat and in close proximity to the cups are drawn in a counter-clockwise direction with the dolly and at the same time to a certain extent, the vacuum cups tend to draw the cleansing fluid through the clothes. Upon reversal, the clothes are dragged along with the cups and circulated around the vat in the opposite direction. It will be noted that the cups face in opposite directions, so that when the dolly is oscillating, because less 40

45

50

55

55

resistance is offered to the passage of the dolly through the cleansing fluid by the hemi-spherical surface of the blades than by the cups, the resultant action although substantially equal in both directions is such as to cause a slight tendency for the clothes and washing fluid to circulate predominately around the vat in one direction. Although as has been said, this resultant movement of the clothes in one direction is slight, the clothes to casual observation appearing to be moved with equal force in both directions, it is sufficient when combined with the natural agitation set by the blades to cause new clothes surfaces to be constantly presented to the washing action of the vacuum cups.

The action of the dolly shown in Figures 4 and 5 is substantially the same as that described with respect to Figure 1 with the exception that substantially the entire contents of the vat from the bottom of the vat to the surface of the liquid is subjected to the vacuum cup action above described.

It is apparent that I have provided a novel oscillatable dolly which is adapted to secure an effective vacuum cup action on the clothes and that various modifications may be made in the form and relation of parts thereof. I, therefore, do not desire to restrict myself to the details of the construction and form illustrated except where the same are specifically included in the claims hereto appended, as various changes and modifications may be made without departing from the scope of my invention.

I claim:

35 1. In a machine for washing clothes, a vat, an agitator mounted therein, said agitator comprising an upstanding central portion and a plurality of blades extending from the central portion.

each of said blades presenting a hemispherical unobstructed surface on one side to the washing fluid and being cup-shaped on the other side, and means for oscillating said agitator, the cup-shaped surfaces of said blades being arranged to produce circulation of clothes and washing fluid in one direction around the vat.

2. A machine for washing clothes comprising a vat for containing clothes to be washed and washing fluid, an oscillatable agitator mounted in said vat, means extending through the bottom of the vat for oscillating said agitator, said agitator comprising a central portion and a pair of clothes washing elements radiating outwardly from said central portion, each of said clothes washing elements presenting a hemispherical surface to the washing fluid on one side and a vacuum cup surface to the washing fluid on the other side, said vacuum cup surfaces facing in opposite directions.

3. In a machine for washing clothes, a vat for containing the clothes and washing fluid, an oscillatable agitator mounted in said vat, means extending through the bottom of the vat for oscillating said agitator, said agitator comprising a central post and a plurality of blades extending from said central post, said blades each having a hemispherical unobstructed surface presented to the clothes and washing fluid in one direction of rotation of the agitator and having a cup-shaped surface presented to the clothes and washing fluid in the other direction of rotation of the agitator whereby the opposite faces of the blades exert an unequal thrust to cause the clothes and washing fluid to circulate in one direction around the vat.

HERMANN HILL.
